UNITED STATES PATENT OFFICE.

WILLIAM A. PARDOE, OF NEW YORK, N. Y.

WHISTLE.

No. 805,817.

Specification of Letters Patent.

Patented Nov. 28, 1905.

Application filed July 24, 1905. Serial No. 270,989.

To all whom it may concern:

Be it known that I, WILLIAM A. PARDOE, a citizen of the United States, residing at New York city, in the county of New York and State 5 of New York, have invented certain new and useful Improvements in Whistles, of which the following is a specification.

My invention relates to musical instruments, and more particularly to whistles designed to 10 be held in the mouth of the user thereof.

The object of my improvement is to provide 15 a whistle of a richer, fuller, and more melodious tone and of greater compass than others of its class, of greater sonority, and to provide the same with a reed so arranged that the air entering the whistle may be caused to pulsate and its vibrations be reinforced, whereby 20 a singing quality is given to the sounds emitted, a quality absent from whistles of like simplicity to this of mine.

To this end my invention consists in a certain arrangement of parts and combinations of elements as described in the following specification and set forth more specifically in the 25 appended claims.

In the accompanying drawings I have shown a whistle constructed in accordance with my invention.

In the drawings, Figure 1 is a perspective 30 view. Fig. 2 is a longitudinal section along the major axis of the instrument. Fig. 3 is an end elevation viewed from the opening of the resonator.

Like numerals designate like parts in the 35 several figures.

The instrument consists of a mouthpiece and a resonator. The mouthpiece consists of a whistle proper formed of upper and lower flat plates 2, closed at their rear and side 40 margins and unpierced except for the registering air-entrance openings 3 common to this class of whistles. The front end of the mouthpiece extends outward into a resonator or horn 4. In order to give a depth and richness to the notes, I give to the resonator a rounded contour. Preferably it is elliptical 45 in transverse section, as shown in Fig. 2, the major axis of the ellipse being parallel to the plane of the mouthpiece, and the upper and lower surfaces of the resonator are curved 50 from front to rear, as shown in Fig. 3. I have discovered that such a contour by reason of its curvature gives a more liquid, softer, and more musical tone than when the resonator is flat and the angles sharp, takes away 55

from the ear-piercing shrillness usual to whistles of this class, and strengthens the harmonics of the fundamental note given by the whistle.

In order to provide means whereby the 60 whistle may be held in engagement by the lips of the player, I form the upper and lower plates 2 with transverse registering corrugations 5, raised up from the surface of the plate. These I locate at the junction of the 65 mouthpiece with the resonator.

Transversely across the resonator on a line with the mouthpiece and parallel thereto I place the reed 6. This reed may be made of any suitable material, preferably of thin sheet 70 metal, elastic enough to vibrate through the passage of air from the mouthpiece. This reinforces the vibrations in the resonator and assists in giving a peculiarly flute-like quality of tone.

It is to be noted that the mouthpiece is 75 closed at the ends. This prevents the escape of air from the end of the mouthpiece and permits the entire volume of air to be used to create a musical note. In addition to this 80

the closed ends of the mouthpiece prevent the accumulation of saliva within the whistle and its consequent obstruction. In whistles having the mouthpiece open at the sides the accumulation of saliva demands that the whistle 85 be shaken or cleaned every little while, thus interfering with its success as a musical instrument. Heretofore whistles of this character have been provided with slots in place of the corrugations 5, said slots being closed 90 by the lips of the player. It has been a matter of more or less difficulty to keep said slots closed at all times, as the slots are merely used for the retention of the instrument in the mouth, and as the opening of either one 95 of the slots would interfere with the production of sound I have devised these corrugations, which afford equally good means for holding the whistle, while at the same time they are always closed and require no effort 100 on the part of the player to keep them so.

The advantages of my improvements are 105 obvious. No breath is wasted. There is no difficulty in holding the instrument in the mouth, and the bell-shaped resonator and its reed soften and deepen the sound and give to it a quality which a whistle having a resonator of a different form lacks. Another advantage results from closing the ends of the mouthpiece in that no saliva enters the whis- 110

tle. This is particularly troublesome in the other forms of whistle having an open-ended mouthpiece and necessitates a clearing out of the whistle at very frequent intervals.

5. The instrument can be cheaply made, requires no skill in the playing, and is of considerable musical value.

Having described my invention, what I claim is—

10. 1. A whistle comprising a mouthpiece formed of two separated plates open at the front and having registering air-inlet openings; and a resonator expanding outward from the front opening of the mouthpiece; 15 said resonator being rounded in general contour, substantially as described.

20. 2. A whistle comprising a mouthpiece formed of two separated plates open at the front and having registering air-inlet openings; and a resonator expanding outward from the front opening of the mouthpiece, said resonator being elliptical in section, the major axis of the ellipse being parallel to the plane of the said mouthpiece, substantially 25 as described.

30. 3. A whistle comprising a mouthpiece formed of two separated plates, closed at the rear and open at the front and provided with registering air-inlet openings, and a resonator expanding outward from the front opening of the mouthpiece, said whistle having corrugations on its upper and lower outer faces for engagement by the lips of the user, substantially as described.

35. 4. A whistle comprising a mouthpiece formed of two separated plates closed at the rear and open at the front and provided with two registering air-inlet openings; a resonator expanding from the front opening of the 40 mouthpiece and a reed located in said resona-

tor across the opening of the mouthpiece, substantially as described.

5. A whistle comprising a mouthpiece formed of two separated plates closed at the rear and sides but open at the front and having two registering air-inlet openings, a resonator of a general elliptical contour expanding from the front opening of the mouthpiece and a reed located transversely across said resonator, the inner edge of said reed being 45 adjacent to the opening of the mouthpiece into the resonator, substantially as described.

6. A whistle comprising a mouthpiece formed of two separated plates closed at the rear and sides, but open at the front and having two registering air-inlet openings, a resonator of a general elliptical contour expanding from the front opening of the mouthpiece, the major axis of the ellipse being parallel to the plane of the mouthpiece, corrugations 50 on the outer surfaces of the whistle at the junction of the resonator with the mouthpiece, and a reed located transversely across said resonator, whose inner edge is adjacent to the opening of the mouthpiece into the 55 resonator, substantially as described.

7. A whistle comprising a mouthpiece formed of two separated plates open at the front, closed at the sides, and having registering air-inlet openings; and a resonator expanding outward from the front opening of the mouthpiece, substantially as described.

In testimony whereof I have signed my name to this specification, in the presence of two subscribing witnesses, this 20th day of July, 1905.

WILLIAM A. PARDOE.
